UNITED STATES PATENT OFFICE.

GEORGE E. KIMBALL, OF FRANKLIN, MASSACHUSETTS.

DEVICE FOR STRETCHING CARD-CLOTHING.

SPECIFICATION forming part of Letters Patent No. 320,795, dated June 23, 1885.

Application filed January 15, 1884. (No model.)

To all whom it may concern:

Be it known that I, GEORGE E. KIMBALL, a citizen of the United States, and a resident of Franklin, in the county of Norfolk and State 5 of Massachusetts, have invented certain new and useful Improvements in Devices for Stretching Card-Clothing; and I do hereby declare that the following is a full, clear, and exact description of the invention, which will 10 enable others skilled in the art to which it appertains to make and use the same, reference being had to the accompanying drawings, which form a part of this specification, and in which—

15 Figure 1 is a perspective view of a portion of a carding-cylinder, showing my improved device for stretching the card-cloth in position. Fig. 2 is a similar view of the device detached. Fig. 3 is a top view of the same; 20 and Fig. 4 is a longitudinal vertical section of the same.

Similar letters of reference indicate corresponding parts in all the figures.

25 My invention has relation to devices for stretching card-clothing upon carding-cylinders; and it consists in the improved construction and combination of parts of the same, as hereinafter more fully described and claimed.

30 In the accompanying drawings, the letter A indicates the carding-cylinder upon which the card-sheets B are stretched parallel with the axle of the cylinder. When the carding-cylinder is used, one or more of the sheets 35 will often become loosened, forming blisters, and the points of the cards are apt to become worn unduly by coming in too close contact with the doffer, thus impairing the usefulness of the cards.

40 For the purpose of stretching the blistered card-sheets, it has been customary to remove the sheets, and thereupon tacking them upon the cylinder in the same manner as in tacking new sheets upon the cylinder, and this process, together with the subsequent sharpening 45 of the teeth, has consumed a great length of time, in which the machine has been obliged to stand idle; and to avoid this waste of time, and to accomplish a speedy and effect- 50 ual stretching of the blistered card-sheets, I

have constructed the device which I will proceed to describe. This device consists of a bar, C, having a longitudinal recess, D, in its underside, and having two or more or less downwardly-bent arms, E, provided with sharpened points F, and the upper side of the bar has two shoulders, G, forming a recess between them.

A bar, H, having arms I, similar to the arms E, and sharpened points J, at the ends 6 of the arms, slides and fits in the longitudinal recess in the under side of the bar C, and is provided with an upwardly-projecting pin or bolt, K, which projects up through and slides in a longitudinal slot, L, in the bottom 6 of the recess formed by the shoulders G, and is provided at its upper end with an eccentric disk, M, of a diameter equal to the width of the recess, thus fitting snugly between the shoulders, and having two thumb-wings, N, 7 or similar means for affording a good hold upon its upper side.

It will now be seen that by turning the eccentric by its wings the sliding bar will be drawn farther in or pushed farther out in the recess in 7 bar C, thus shortening or lengthening the distance between the sharpened points, and if a blister is found upon one of the card-sheets, which is easily discovered by the shining appearance of the worn card-teeth, the tacks confining the one edge of the sheet are removed, the stretcher placed with its points penetrating into the sheet in its shortened position, whereupon the eccentric is turned, lengthening the stretcher until the sheet is stretched to its proper 8 width and the lower edge again tacked down, which process may be continued until the entire blister is stretched, thus avoiding the loss of time accompanying the process of removing the entire covering of sheets and again 9 replacing them.

Having thus described my invention, I claim—

The combination of a bar having downwardly-bent pointed outer ends, having a longitudinal recess in its under side, and having two shoulders forming a recess between them, having a longitudinal slot at its inner portion, with a bar having downwardly-bent pointed outer ends, sliding with its inner end in the 1

longitudinal recess in the other bar, a pin or bolt projecting through the slot between the shoulders upon the recessed and slotted bar, and an eccentric disk turning upon the upper end of the said pin, fitting between the shoulders upon the recessed bar, and having wings or similar means for holding it while turning it, as and for the purpose shown and set forth.

In testimony that I claim the foregoing as to my own I have hereunto affixed my signature in presence of two witnesses.

GEORGE E. KIMBALL.
